FIG. 1 is a perspective view of a golf score pad platform with collapsible/adjustable fresnel lens magnifier showing our new design;

FIG. 2 is a front elevational view thereof;

FIG. 3 is a top plan view thereof;

FIG. 4 is a right side elevational view thereof, the left side elevational view being a mirror image thereof;

FIG. 5 is a rear elevational view thereof; and,

FIG. 6 is a perspective view showing the golf score pad platform with collapsible/adjustable fresnel lens magnifier in use; the broken lines depict environmental structure for illustrative purposes only and form no part of the claimed design.
